F. LE G. BRYANT

REFRIGERATING UNIT

Filed Aug. 11, 1927

Forrest LeGrand Bryant,

334 H. Brewster & Co

Attorney:

UNITED STATES PATENT OFFICE.

FORREST LE GRAND BRYANT, OF JOHNSON CITY, NEW YORK, ASSIGNOR TO BRYANT ELECTRIC REFRIGERATOR CORPORATION, OF WILMINGTON, DELAWARE, A CORPORATION OF DELAWARE.

REFRIGERATING UNIT.

Application filed August 11, 1927. Serial No. 212,253.

The invention relates to refrigerators of the compressor type and has reference more particularly to the heat-absorbing unit in which the usual boiling action of the refrigerant takes place, said unit being provided with means to receive pans for freezing water or other fluids.

It is the object of the invention to provide a new and improved, exceptionally simple and inexpensive and very efficient refrigerating unit in which a plurality of shells which receive the fluid-freezing pans, are substantially surrounded by the refrigerant so as to obtain maximum efficiency and at the same time permit the use of a smaller quantity of refrigerant than can ordinarily be used, this being not only of advantage for economy in charging the apparatus, but in case of any leaks, as less of the refrigerant can run from the apparatus than if more were used.

With the foregoing in view, the invention resides in the novel subject matter herein-after described and claimed, the description being supplemented by the accompanying drawing.

Fig. 1 is a vertical sectional view through a refrigerating unit constructed in accordance with my invention, showing it operatively connected with the usual float tank, to which the liquid refrigerant is pumped and from which the gas generated by the boiling of the liquid, is drawn.

Fig. 2 is a vertical transverse sectional view on line 2—2 of Fig. 1.

The preferred form of construction has been selected for illustration in the present application and while this construction will be herein specifically described, it is to be understood that within the scope of the invention as claimed, variations may be made.

In the drawing above briefly described, the numeral 3 designates an outer shell for the refrigerant, at least the vertical side walls, the rear wall and the bottom wall of said shell, being provided with heat-conducting fins 4. The top wall of the shell 3 is provided with upstanding nipples 5 integral therewith and flanged at 6 for connection with similar nipples 7 on the bottom of a float tank 8. This tank contains the usual liquid inlet valve 11 controlled by a float 12, the refrigerant sup-

ply tube 13 leads to said valve, and a gas discharge tube 14 leads from the upper portion of the tank. The float-controlled valve 11 controls the level of liquid in the tank 8 in the usual manner, this liquid of course also fills the shell 3 through the communicating nipples, the boiling of the liquid takes place in said shell, the gas rises through the communicating nipples into the upper portion of the tank 8, and said gas is pumped off through the tube 14.

The front end of the outer shell 3 is open and is provided with an integral outstanding flange 15 to which a removable front wall 16 is secured by bolts 17, an appropriate gasket 18 being interposed between said flange and wall. At suitable locations, the front wall 16 is formed with openings 19 through which to insert the usual fluid-freezing pans (not shown). This front wall carries a plurality of inner shells 20 preferably of rectangular form, said shells having open front ends and being at said ends integrally joined to said front wall around the openings 19, said shells 20 being adapted to receive the fluid-freezing pans. These shells are spaced from all walls of the outer shell 3 with the exception of the front wall 16 and they are also spaced from each other, so that each of them may be substantially surrounded by the refrigerant to obtain unusual efficiency, making it possible to freeze water, custards, etc., in a shorter period of time than is now possible.

In case repairs should be necessary to one of the shells 20 or to the shell 3, the plate 16 may be unbolted from the shell 3, permitting all of the shells 20 and said plate 16 to be removed as a single unit from the shell 3, thus giving access to the interior of shell 3 or to the exteriors of the shells 20, as may be required.

Attention is again invited to the fact that while the preferred form of construction has been shown and specifically described, variations may be made within the scope of the invention as claimed.

I claim:—

A refrigerating unit comprising an outer shell to contain a refrigerant, said shell being provided with external heat-conducting fins, with a nipple at its top for connection with a float tank, and with a removable front wall,

the latter being formed with spaced openings through which to insert fluid-freezing pans, and a plurality of inner pan-receiving shells having open front ends integrally joined to said front wall and communicating with said openings, said pan-receiving shells being spaced from all other walls of said outer

shell and from each other, permitting each inner shell to be substantially surrounded by the refrigerant.

10

In testimony whereof I have hereunto affixed my signature.

FORREST LE GRAND BRYANT.
